WILLIAM H. ORPEN, JR., OF BROOKLYN, NEW YORK, ASSIGNOR TO INTERNATIONAL TYPESETTING MACHINE COMPANY, OF NEW YORK, N. Y., A CORPORATION OF NEW YORK.

MAGAZINE FOR TYPOGRAPHICAL MACHINES.

1,156,033.

Specification of Letters Patent.

Patented Oct. 5, 1915.

Application filed February 4, 1914. Serial No. 816,563.

To all whom it may concern:

Be it known that I, WILLIAM H. ORPEN, Jr., a citizen of the United States, residing at Brooklyn, in the county of Kings and State of New York, have invented new and useful Improvements in Magazines for Typographical Machines, of which the following is a specification.

The present invention relates to improvements in typographical machines and more especially to those of the linotype class employing a magazine provided with channels to contain matrices, the latter being distributed into the appropriate channels at one end of the magazine and discharged from the opposite end of the magazine under the control of escapements. In machines of this class it has been customary heretofore to place the magazine in an inclined position in order to avoid excessive speed of the matrices in the magazine which would damage the matrices and the escapements which engage and arrest them.

The primary object of the present invention is to provide means for controlling the speed of the matrices while traveling in the magazine whereby the magazine may be placed in a vertical position or at a steeper inclination than heretofore possible without liability of damage to the matrices or the arresting and controlling escapements. The invention, however, is applicable generally to any chute or passageway of the machine through which the matrices fall or descend by gravity whereby the speed of movement of the matrices is retarded or controlled as desired.

The accompanying drawing is a perspective view, partly in section, showing the present invention applied to a vertical magazine which latter is adapted to handle matrices of the ordinary type.

In the present instance the magazine is shown constructed of a pair of plates 1 and 2 which are held in the usual or any other suitable way in appropriately spaced relation to accommodate the matrices edgewise between them. In the present arrangement, the matrices are introduced into the top or upper end of the magazine by distributor mechanism similar to that ordinarily employed, the same comprising a pair of upper screws 3 and 4, a lower screw 5, and a toothed or ribbed distributor bar 6, the screws feeding the matrices along the under

side of the distributor bar until they reach their respective channels in the magazine. The construction shown is adapted to handle matrices of the ordinary type, each matrix M having upper ears or lugs m and lower ears or lugs m' . As the matrices reach positions above their respective channels in the magazine they drop from the distributor bar into the magazine and gravitate toward the lower end of the magazine, they being arrested either by dropping upon matrices already contained in the lower portion of the magazine or by escapement means. In the present instance, an escapement 7 is provided for each magazine channel, this escapement having two pawls, the lower of which normally engages the lowermost matrix in the respective channel. The escapement is held normally in this position by a lever 8 which is pivoted at 9 and is acted on by a spring 10. The escapement is actuated to release and cause delivery of the lowermost matrix which is retained on the lower pawl of the escapement by an escapement actuating rod 11 which is operated by the usual keyboard mechanism. Obviously, any other appropriate type of escapement means may be used as a substitute for that shown.

12 and 13 designate the channels formed in the inner faces of the plates 1 and 2, these channels being of a number corresponding to the number of matrices which the magazine is designed to contain. Ordinarily these channels are straight from top to bottom or end to end of the magazine. According to the present invention, however, these channels are formed with waves, corrugations or other appropriate irregular shape whereby a sinuous path is provided which will impart to the matrices a swinging, zig-zag, wiggling or other motion of a character which will retard or check the fall or descent of the matrices, although the matrices at all times will be free to descend by their own weight, thereby avoiding the possibility of clogging the matrix passageway, the speed of descent of the matrices being retarded or checked to such extent that should any of the matrices fall or descend the entire height of the magazine it will not produce a blow sufficient to injure either the matrix or the escapement. In the preferred construction which is shown waves or corrugations are formed in the matrix chan-

nels of the magazine, and these waves or corrugations are preferably arranged so that they alternate, that is to say, the low part of the wave or corrugation 14 in one plate is opposite to the high part of the wave or corrugation 15 in the opposite plate. During the descent of the matrix, the ears or lugs on the upper and lower ends thereof follow the waves or undulatory surfaces of the matrix channels whereby the matrix is caused to swing or wiggle as it descends through the zig-zag or sinuous passageway which is thus provided. It is preferable not to extend the waves or corrugations to the top or bottom of the magazine, that is to say, the matrix channels at the top and bottom of the magazine are preferably straight, as shown. This will allow each matrix to drop freely into the magazine and thus clear the distributor and any succeeding matrix on the distributor bar and allow the matrices at the lower end of the magazine to be delivered freely and at unretarded speed.

I claim as my invention:—

- 25 1. In a machine of the linotype class, a channel or passageway through which matrices fall, said channel being straight but having its walls irregular in form to retard the movement of the matrices.
- 30 2. In a machine of the class described, a matrix passageway through which matrices are adapted to fall and having means for imparting oscillatory movement to the matrices to retard the speed of falling thereof.
- 35 3. In a machine of the class described, a sinuous passageway through which matrices are adapted to fall, the passageway being straight in its general direction.
- 40 4. In a machine of the class described, a passageway through which matrices are adapted to fall, said passageway being

straight in its general direction and having undulatory surfaces operative to oscillate and thereby retard the falling movement of the matrices.

5 5. A channel or chute through which matrices fall endwise, two opposite guiding surfaces of said chute being formed with alternate waves or corrugations to oscillate the matrices edgewise and thereby retard their speed and to guide the matrices in a substantially straight direction.

10 6. In a machine of the class described, a matrix magazine having channels through which matrices are adapted to fall, and escapement means for arresting the falling and controlling the delivery of matrices from each channel, said channels being straight longitudinally and having irregular surfaces to engage and oscillate and thus retard the fall of the matrices while maintaining the course of the matrices substantially straight.

15 7. In a machine of the linotype class, in combination with a matrix magazine adapted to receive matrices in its upper end from a distributor, and having an escapement at its lower end to control the delivery of matrices therefrom, a series of substantially straight channels in said magazine through which the matrices freely fall, all or some of said channels being irregular, thereby causing the matrices to be oscillated edgewise while maintaining a substantially straight course of descent.

20 In testimony whereof I have hereunto set my hand in presence of two subscribing witnesses:
